UNITED STATES PATENT OFFICE.

JOHN WILLIAM COOK, OF EASTLEIGH, DIDSBURY, ENGLAND, ASSIGNEE TO ANGLO-AMERICAN TEXTILE MACHINERY COMPANY, OF ABINGTON, MASSACHUSETTS, A CORPORATION OF MASSACHUSETTS.

KNOTTING DEVICE.

1,188,902.

Specification of Letters Patent. Patented June 27, 1916.

Application filed February 20, 1911. Serial No. 609,572.

To all whom it may concern:

Be it known that I, JOHN WILLIAM COOK, of Eastleigh, Didsbury, in the county of Lancaster, England, have invented certain new and useful Improvements in Knotting Devices, of which the following is a specification.

My invention relates to a device for the purpose of tying knots in yarns, threads, 10 twine or the like.

My invention comprises a novel form of knotting device comparatively light in weight and having the mechanisms for operating the knotting bill and the drawing-off device inclosed.

My invention further comprises an arrangement of parts whereby the knot can be tightened and the said knot pulled off the knotting bill by means of a rotatable pulling off device driven from the same gearing which drives the knotting bill and an arrangement of parts whereby the said pulling off device does not clamp the thread and thus injure it.

Hitherto it has been customary to employ loop tightening and knot drawing-off devices which grip or clamp the thread during the operation. I employ as set out a rotatable loop tightening and pulling off device 30 to wind on to it for the purpose indicated.

Figure 1 of the accompanying drawing is a front elevation of my improved knotting device. Fig. 2 is a front elevation similar to Fig. 1 with cover removed. Fig. 3 is a 35 plan view. Fig. 4 is a section view through 1-2. Fig. 5 is a side elevation.

In a preferred construction I employ a suitable metal casting or the like A in the form of a case or box and having a downwardly projecting extension B which fits against the hand of the operator. Within the case A I mount a short transverse shaft C or the like carrying a small primary quadrant D the said quadrant D having 45 teeth cut in its face. The transverse shaft C extends through the cover A' of the case and to the projecting portion C' a handle E having a thumb piece E' is attached.

The teeth of the quadrant D mesh with 50 the teeth of a small pinion F suitably mounted and carrying a secondary quadrant or segmental rack H. I prefer to employ a known form of knotting bill I the said knotting bill being carried upon a short ver-

tical shaft K suitably supported and rotatable upon a stud, or bearing point L. The knotting bill I may either comprise a single piece suitably split or cut to form two outer jaws or members or two separate jaw members between which is disposed a movable 55 jaw member. Formed as part of or attached to the case A is a collar or flange M which collar or flange surrounds the vertical shaft K carrying the knotting bill and is eccentrically disposed in relation to the axis of 60 the said knotting bill shaft. As is known I form the movable jaw member with a cam shaped shank which upon the rotation of the shaft K comes in contact with the inner face of the collar or flange M being consequently actuated by the flange or collar. The knotting bill is sharpened in the usual manner to insure the severance of the 65 threads when desired.

Upon the knotting bill shaft K a toothed 70 wheel N is mounted which engages with the teeth of the secondary quadrant or rack H. It will be understood therefore that movement of the rack H in either direction will impart movement to the wheel N and consequently to the knotting bill shaft K. I employ a loop tightener and drawing off hook O which is carried on or forms part of a second vertical shaft or rod P which is parallel 75 with the shaft K. The said drawing off hook projects through the upper portion of the case A in close proximity to the knotting bill I. Upon the shaft P, I mount a toothed wheel R having helical or other suitably shaped teeth the teeth of the said wheel 80 R meshing with the teeth of the quadrant or rack H. I form with the case cover A' or attach to the said cover or to any convenient part of the device a hook or the like S. I attach the case cover A' to the case A by 85 means of screws T or other suitable means. The yarns or threads V are placed under the hook of the drawing off device O beneath the knotter bill I and under the stationary hook S. The thumb piece E' is depressed 90 and the short shaft C rotated bringing about the rotation of the knotting bill shaft K. The knotting bill I acts in the manner of known knotting bills to form the knot and sever the ends. The drawing off device O 95 which rotates with the knotting bill I serves to draw the knot tight and to draw the knotted threads clear of the knotting bill when the 100

105

loose ends have been severed. The parts are returned to their original positions by means of a spring X which is threaded on and controls the short transverse shaft C. 5 I can employ any form of spring arranged in any suitable manner to control the transverse shaft C and the handle E and thumb piece E'.

What I claim as my invention and desire 10 to secure by Letters Patent is:—

1. A knot tying device comprising a closed casing having substantially flat sides and a curved wall connecting the sides, a loop 15 tightener and a knotting bill rotatably mounted in said case and having their operative portions projecting from the curved wall of the casing, the axes of rotation being parallel, and means including a primary and a secondary quadrant and rotary toothed members meshing with said quadrants, for actuating said tightener and bill.
2. A knot tying device comprising a closed casing having substantially flat sides and a curved wall connecting the sides, a loop 25 tightener and a knotting bill rotatably mounted in said case and having their operative portions projecting from the curved wall of the casing, the axes of rotation being parallel, and gearing within the casing, including a primary and a secondary quadrant and rotary toothed members meshing with said quadrants, for effecting the relative operation of the tightener and bill.
3. A knot tying device comprising a closed

casing having substantially flat sides and a 35 curved wall connecting the sides, a handle extending rigidly from the casing, a loop tightener and a knotting bill rotatably mounted in said casing and projecting through the wall opposite the handle, the 40 axes of rotation of the tightener and bill being parallel, and gearing within the casing including a primary and a secondary quadrant and rotary toothed members meshing with said quadrants, to effect the relative 45 rotation of the tightener and bill.

4. A knot tying device of the character described comprising a closed box or case, a knotting bill having a shaft mounted in said case, a loop tightener and knot drawing-off 50 device having a shaft mounted in said case, a toothed quadrant or sector, a pinion, a secondary toothed quadrant or sector, a toothed wheel mounted on the knotting bill shaft and engaged with said secondary quadrant 55 or sector, a helical gear secured to the shaft of the loop tightener and also meshing with said secondary quadrant or sector, and a spring controlled thumb piece and connections therefrom for actuating the said quadrants.

In testimony whereof I have affixed my signature, in presence of two witnesses.

JOHN WILLIAM COOK.
